(57)

CLAIM

An ornamental design for pants, as shown and described.

DESCRIPTION

FIG. 1 is a right side perspective view of pants showing my new design;

FIG. 2 is a left side perspective view of the pants shown in FIG. 1;

FIG. 3 is a front view of the pants shown in FIG. 1;

FIG. 4 is a rear view of the pants shown in FIG. 1; and,

FIG. 5 is a right side view of the pants as shown in FIG. 1. The broken lines in the FIGURES depict portions of the pants that form no part of the claimed design.

1 Claim, 5 Drawing Sheets(56)
